UNITED STATES PATENT OFFICE

154,901

DESIGN FOR A COMBINED CANDELABRUM AND FLOWER HOLDER

Jeff David Bussey, Atlanta, Ga.

Application December 22, 1948, Serial No. 150,325

Term of patent 14 years

(Cl. D48—2)

To all whom it may concern:

Be it known that I, Jeff David Bussey, a citizen of the United States of America and a resident of the city of Atlanta, Fulton County, State of Georgia, have invented a new, original, and ornamental Design for a Combined Candelabrum and Flower Holder, of which the following is a specification, reference being had to the accompanying drawing, forming a part thereof.

In the drawing,

Figure 1 is a front elevational view of a combined candelabrum and flower holder showing my new design.

Fig. 2 is a right side elevational view with the lower portion of the support omitted.

Fig. 3 is a top plan view.

Fig. 4 is an enlarged vertical sectional view in the plane of line 4—4 on Fig. 1, with a small upper portion shown in elevation.

Fig. 5 is an enlarged fragmental view more clearly indicating the support for the candle holders.

I claim:

The ornamental design for a combined candelabrum and flower holder, substantially as shown.

JEFF DAVID BUSSEY.
